W. JONES.

Gas Stove.

No. 79,230.

Patented June 23, 1868.

United States Patent Office.

WILLIAM JONES, OF CHELSEA, MASSACHUSETTS.

Letters Patent No. 79,230, dated June 23, 1868.

IMPROVEMENT IN GAS-HEATERS.

The Schedule referred to in these Letters Patent and making part of the same.

TO ALL WHOM IT MAY CONCERN:

Be it known that I, WILLIAM JONES, of Chelsea, in the county of Suffolk, and State of Massachusetts, have invented an Improvement in Burning Gas for Heating; and I do hereby declare that the following, taken in connection with the drawings which accompany and form part of this specification, is a description of my invention sufficient to enable those skilled in the art to practise it.

It has long been known that the mixture of atmospheric air and common street-gas, which will burn with blue flame, is a convenient means for heating, and it is to the detail by which such mixture is made and applied that my invention relates.

My invention consists; first, in a peculiar construction of gas-cock, within which the mixture is made, and from and through which it is supplied to the point where the combustion takes place; and, second, in an arrangement of parts by which, in confined spaces, like calender-rolls, for example, pure atmospheric air is obtained for mixing with the gas, instead of vitiated air, such as exists within the calender-roll where the flame is burning. The ordinary way of mixing air and gas to be burned for the purpose of producing heat instead of light, is to cause the air to enter the pipe conveying the gas near the point where the mixture is consumed.

In heating calendering-cylinders in the common way, with apertures in the pipe between the gas-cock and the end of the pipe at which the mixture is burned, said apertures receiving air from within the calendering-cylinder for mixing with the gas, it has always happened that shortly after starting the flame, and as soon as the air in the cylinder becomes vitiated, the flame will smoke and coat the interior of the cylinder, thus impairing its efficiency and increasing the consumption of the gas.

This difficulty I have remedied by placing not only the gas-cock outside of the heated chamber, but the aperture through which the gas is supplied with the air which is to be intermixed therewith.

In the ordinary mixing-apparatus, the atmospheric air is made to flow in jets into a pipe filled with gas. I obtain improved results for admitting the gas in fine jets into a pipe or chamber, through which a current of atmospheric air passes, and where the pipe conveying the mixture of air and gas is horizontal, or nearly so, I make the opening through which the air enters to mingle with the gas, at such a distance below the inlet of the gas and the outlet of the mixture, that neither the gas nor mixture will escape at the air-inlet, the gas and the mixture being both lighter than the air, are, as it were, sealed from escape by the incoming current of air.

The drawing shows, in sectional elevation, an apparatus embodying both parts of my invention.

a denotes a calendering-roll or cylinder, mounted so as to turn on a hollow pivot, *b*, in the bearing *c*. Through the hollow pivot or journal, the pipe *d* passes, having its end turned upward, toward the material of the roll which is to be heated by combustion of a mixture of gas and air at the open end of said pipe.

Outside of the bearing is a plug-cock, of peculiar construction, the purpose of the cock being to admit both air and gas, and to cause them to mingle before passing into the pipe *d*. *e* is the plug of the cock, working in the barrel *f*, *g* being the end of the cock to which the gas-conveying pipe is fixed, while the other end, *h*, of the cock, is fixed to the pipe *d*, conveying the mixture of air and gas.

The plug *e* is hollow, with an opening at the lower end thereof, and the chamber *i* in the plug is made to communicate, by a large opening, *j*, with the pipe *d*, and with the gas-pipe, by several minute holes, *k k*.

The gas flows into the chamber *i*, in fine streams, through *k k*, in the direction indicated by the arrows, and mingles with the atmospheric air present in the chamber *i*, and, as the mixture, which is lighter than the air, moves in the pipe *d* to supply the flame, the atmospheric air moves up the chamber *i*, as indicated by the arrow on the drawing.

As in any cock, a slight turn of the plug shuts off the supply of gas when the flame at the end of *d* is to be extinguished.

I claim, for the purpose of mixing air and gas to be burned, a plug-cock, having a long, open, chambered plug, with inlets *k k* and outlet *j*, arranged to operate substantially as described.

Also, in connection with a burner, arranged within a confined space, provision substantially as shown and described, for supplying fresh unvitiated atmospheric air, to be mingled with the gas passing to the flame, as set forth.

WM. JONES.
